DESIGN FOR A COMBINED BEZEL, DIAL, AND HANDS FOR A CLOCK OR SIMILAR ARTICLE

Gordon Miller Buehrig, Auburn, Ind., assignor to
Auburn Automobile Company, Auburn, Ind., a
corporation of Indiana

Application May 31, 1935, Serial No. 57,976

Term of patent 7 years

To all whom it may concern:

Be it known that I, Gordon Miller Buehrig, a citizen of the United States, residing at Auburn, in the county of De Kalb and State of Indiana, have invented a new, original, and ornamental Design for a Combined Bezel, Dial, and Hands for a Clock or Similar Article, of which the following is a specification, reference being had to the accompanying drawing forming a part thereof:

Figure 1 of the drawing is a front view of a

combined bezel, dial, and hands for a clock or similar article, showing my new design; and Figure 2 is a side view.

I claim:

The ornamental design for a combined bezel, dial, and hands for a clock or similar article, substantially as shown.

Signed at Auburn, Indiana, this 25th day of May, 1935.

GORDON MILLER BUEHRIG.
